COMPOSITE WINDOW SASH AND SCREEN

Hans Peter Gronbech, Pacific Beach, Calif.

Application January 4, 1932. Serial No. 584,643

13 Claims. (Cl. 156—39)

The present invention relates to improved apparatus for compounding a sliding window sash, and a follower screen detachably attached to said sash and forming an extension of one side edge thereof adapted upon rolling or unrolling to accommodate itself to the movement and position of the sash.

More particularly the invention resides in the novel construction of the window framing and the parts housed therein which coordinate with the supplementary parts to insure a workable and efficient combination.

The supplementary parts referred to are the awning and screen roller attachment. The construction of these parts and their operating mechanisms separately considered, being new and novel, have been made the subject matter of other applications for Letters Patent now pending. These applications were filed on December 18, 1931, and their serial numbers are 581,881 and 581,882 respectively, the latter of which matured into Patent No. 1,877,853 on Sept. 20, 1932.

An important object of the invention in addition to more effectively meeting the requirements outlined supra, is to improve in general upon applicant's invention entitled Combination screen and glass window construction filed June 25, 1930; Serial No. 463,696, and patented

30 Mar. 15, 1932, No. 1,849,371.

An important object of the invention is the incorporation of improved means for connecting and disconnecting the sash to the screen.

An important object of the invention is the incorporation of improved means for obtaining a more perfect balance of the sash and the screen.

Still further objects will obviously become apparent as the invention is hereinafter disclosed.

40 In the accompanying drawings illustrating the invention:

Fig. 1 is a perspective view of the device.

Fig. 2 is a fragmentary perspective view illustrating the manner in which the sash is fastened to the screen.

Fig. 3 is a fragmentary perspective view taken on line 3—3 of Fig. 1, a portion in the view being broken away to show hidden construction.

Fig. 4 is a fragmentary perspective view taken on line 4—4 of Fig. 1, some parts of the view being broken away to show underlying structure.

Fig. 5 is a section taken through a portion of the sash to show the construction of the sash member.

55 Fig. 6 is a fragmentary elevation of the upper

left hand corner of the device shown in Fig. 1. In this view some parts are broken away to illustrate a portion of the awning roller and screen roller mounting.

Fig. 7 is a fragmentary elevation of the upper 60 right hand corner of the window framing shown in Fig. 1. In this view a portion of the structure is also broken away to show further mounting of the awning roller with its tape whereby it is operated as well as other details.

Fig. 8 is a fragmentary elevation of the lower 65 left hand corner of the window framing shown in Fig. 1, some portions of which are broken away to show existing structure therebehind.

Fig. 9 is a fragmentary elevation of the lower 70 right hand corner of the window framing shown in Fig. 1.

Fig. 10 is an end view of Fig. 6.

Fig. 11 is an end view of Fig. 8.

Fig. 12 is an end view of Fig. 7.

Fig. 13 is an end view of Fig. 9.

Fig. 14 is a plan view of Fig. 6 showing the screen roller.

Fig. 15 is a plan view of Fig. 8 showing the screen roller removed.

Fig. 16 is a plan view of Fig. 7.

Fig. 17 is a plan view of Fig. 9.

Fig. 18 is a side elevation of the movable sash carrier or carriage.

Fig. 19 is a section taken on line 19—19 of 85 Fig. 18.

Fig. 20 is a fragmentary side elevation of the movable sash carrier, a portion of the structure being broken away to show the locking mechanism thereof.

Fig. 21 is a cross section of the sill portion of the window frame illustrating the locking mechanism when the movable sash is in the closed position.

The present improved window frame construction provides for the incorporation of an improved awning unit.

The entire unit which now comprises window sashes, cooperating screen, and awning, together with the co-ordinating parts whereby they are manually operable, come assembled from the factory and ready for installation.

The unit may be installed in Class A buildings without any wood trim on either the interior or exterior of the building, thus complying with the building ordinances with respect to a fire proof structure, or the unit is adapted to be installed in Class C buildings with or without wood trim and in Class D building using 105 110

bull-nose effect with stucco or wood trim as desired.

The device as illustrated in the drawings is shown assembled and mounted in a wooden frame 1, and includes a stationary sash 2 and a movable sash 3.

The movable sash 3 is shown partly opened to illustrate the manner in which it is fastened to the screen 4. The fastening means is further illustrated on a larger scale in Fig. 2. In the latter figure is shown a screw 5 which is partly screwed into the edge face of the sash member.

The screen 4 is provided with an end strip 6, a portion 7 of which extends laterally from the screen.

The end strip 6 is provided with an aperture 8 through which the head of the screw projects. Adjacent the aperture is pivotally mounted a locking lever 9 with which the head of the screw cooperates, there being a slot 10 in the lever 9 which partly encircles the shank of the screw, whereby the lever may be interposed between the head of the screw and the end strip to lock the screen to the sash.

When it is desired to detach the screen from the sash, the locking lever is rotated from the position shown in Fig. 1 to that shown in Fig. 2. The diameter of the aperture 8 is made greater than that of the screw, thus more easily effecting the manual disengagement and engagement of the sash with the screw.

The screen 4 is provided with a screen roller 11 obscurely mounted in the screen roller housing 12, see Fig. 6, from which it is manually unwound and upon which it is automatically wound by the spring 11a as the movable sash is shifted back and forth in front of the stationary sash, thus accommodating itself to any position in which it is desired to place the sash.

Since the structure of this particular screen roller and its cooperating mechanism contributes to the subject matter of the other applications for Letters Patent hereinbefore referred to, and does not form per se a part of the present invention, it is considered unnecessary to dwell further on disclosing remarks other than the foregoing description and the illustration shown in the drawings which are deemed sufficient to identify the structure with its parent invention.

In addition to the screen roller housing 12 at the left of the window, there is provided an awning housing 13 at the top of the window and a housing 14 at the right side of the window somewhat similar to that of the screen roller housing 13.

The awning housing 13 is provided for the installation of the awning roller 15 upon which the fabric 16 of the awning winds and unwinds. Said roller is provided with a trunnion pin 17 at one end and an aperture at its other end into which the pin 18, welded to the upright frame member 28, is adapted to be inserted.

The trunnion pin 17 is journaled in an adjustable three cornered bracket 19. The bracket fits snugly between the upper wall 20 and the lower wall 21 of the housing upon which it slidably rests, there being an adjusting screw 22 whereby the awning on that end is laterally adjusted in relation to its opposite end, in order to maintain the awning in a perfect stretched condition.

The awning roller is made manually rotatable through the medium of the steel tape 23, one

end of which is wound around one end of the roller 15. From the end of the roller the tape is fed downwardly into the housing 14, then through a slot 24 and finally to an operating handle 24a which is moved manually up and down in the slot 25 to extend or retract the awning fabric as desired.

Since the particular structure of the awning proper, its correlated parts and the manner in which it functions, contributes also to the subject matter of another application for Letters Patent hereinbefore referred to, and does not constitute per se a part of the present invention, it is deemed unnecessary, other than what has been shown and described, to identify it with its parent invention, to allude further thereto at this time.

The housings 12, 13 and 14 are made of shapes pressed from narrow gage steel plates. The housings 12 and 14 are of somewhat similar size and shape, and consist of two upright frame members 26 and 27 for the housing 12, and two upright frame members 28 and 29 for the housing 14. The shapes which compose the awning housing 13 are designated by the numerals 30 and 31, the part 30 being considered the header frame, and the part 31 being considered the header moulding.

Likewise the upright frame members 27 and 29 constitute the inner trim or mouldings which are mitered with the header moulding 31 where they meet.

The header 21 of the housing 13 is a pressed angle shape. It is screwed to the header frame 30 and the ends thereof abut and are welded to the upright frame members 26 and 28.

To the header 21 is screwed the spaced horizontal wood strips 32 and 33. These strips run the full width of the header 21 and abut the upright frame member 28 on one side of the window. On the other side of the window they terminate at a point 34 substantially in line with that of the return portion 35 of the header moulding 31, said return portion 35 being fastened to the wood strip 32 by means of wood screws 36 as shown in Figs. 14 and 16.

To the upright frame member 27 at the bevel juncture of the jamb portion 37 with the face portion 38 is welded one edge of a metal strip 39, the other edge of said strip being bent and rounded as at 40.

Interposed between the strip 39 and the jamb portion 37 is the rubber cushion 32', said cushion being fastened to said strip as shown in Fig. 14.

To the upright frame member 26 is fastened a wood strip 41 which is impregnated with oil. The rounded nose-portion 42 of said strip 41 is brought into close proximity with the edge of the rubber cushion. Between the nose 41 and the rounded portion of the metal strip 39, is an opening 43, through which the screen 4 from the roller 11 passes, it being urged to bear upon the nose portion 42 by the edge of the rubber cushion.

There are two flanges 44 and 45 formed in the upright frame members 26 and 27 between which the sash member rests when in the closed position. In the latter position the edge of the sash abuts the rubber cushion. Through the agency of the rubber cushion the closing of the sash is made noiseless. It also makes the window water-proof at this point.

Through the agency of the round nose effect 42 on the impregnated wood strip 41 the screen

Cloth is prevented from sliding on the flange 45, thus eliminating friction, wear, and noise.

The wood strips 32 and 33 form a guide between which the top portion of the screen travels. They also perform another function which will appear later.

At the point 34 where the jamb portion 37 and the return portion 35 meet, the return portion 35 is formed into a downwardly directed lip 46, which fits between the metal strip 39 and the jamb portion 37. It serves as a tenon to bolster and hold that part of the jamb portion 37 intact.

This tenon not only forms a key as described but also acts as a guide in reassembling the upright frame member 27 with its associated parts after it has been removed for the purpose of inspection or otherwise.

The upright frame members 28 and 29 as stated before, conform in general to those designated by the numerals 26 and 27, but with these differences however.

The flanges 47 and 48 between which the stationary sash rests are dissimilarly arranged. The angle strip 49 is riveted to the upright frame member 28 in such a manner that the rubber bumper and weatherstrip 50 can be clampingly interposed between the said frame members 28 and 29 and the said angle strip 49 to make a leak-proof joint at this point.

In addition to the foregoing the upright frame member 29 has a recessed channel portion 51 in which the tape 23 plays.

The channel recess is covered with an auxiliary moulding 52 which is screwed to the member 29. Into the moulding 52 where the end is overlapped is formed a rack. With said rack cooperates the catch of a dog 52a.

The detail description of the frame work of the housings 12, 13 and 14 having been set forth, the construction of the window sill framing and mechanism housed therein will now be described.

The views in the drawings to which the following description generally alludes, consists of Figs. 4, 8, 9, 11, 13, 15, 17, 18, 19 and 20.

The channel 53 is a pressed metal shape. It is screwed to the iron bar 54 by means of screws 55. The bar 54 is bent at a right angle at each end thus forming a return bend 56 and 57 whereby it is secured to the window stool 57 in a manner to serve as a reinforcement therefor.

The channel 53 provides a track in which the ball bearing rollers 58 shown in Figs. 4, 18 and 19 may travel. Said rollers being fastened to a window carriage 59 shown in Fig. 18, upon which the movable sash 3 is mounted.

There is riveted to the window stool 57, a pressed angle shape 60 which runs the full length of the window stool 57. Said shape 60 serves as a guide for the stationary sash 2, over which it rides when it is desired to move the stationary sash for cleaning purposes. Furthermore the shape 60 serves to make the window waterproof under the stationary sash.

There is interposed between the pressed angle shape 60 and the face of the window stool 57 a filler strip 61.

This filler strip is as wide as the stool on which it rests. It runs the full length of the stationary sash and has its inside edge abutting the flange 62 of the window stool. In this manner the strip 61 arrests the water at a point where the stationary sash and movable sash overlap when closed.

The L irons 63 and 64 are secured to the main

frame. The main frame may be considered to be made up of the upright frame members 26, 28 and the header frame 30.

To the L irons 63 and 64 is screwed the window stool moulding 65, and to the L iron 63 is fastened one end of a coil spring 66. The other end of the coil spring is detachably connected to a hook 67 fastened to the ball bearing roller axle 68 on the window carriage 59.

On the left side of the window frame when viewing the drawings in Figs. 8, 11 and 15 it will be noted the pressed angle shape 60 (see particularly Fig. 11) instead of being held away from the window stool by a filler strip 61 is provided with a series of washers 69 interposed therebetween. This construction provides for the egress of water which runs down the movable sash.

The window stool 57 is provided with an upturned flange 62 and an upturned flange 70, the flange 62 being of lesser height than that of the flange 70. It will be seen by referring to Fig. 4, that this offset or difference in height occurs at a point where the stationary sash stops or approximately at the middle of the window frame.

This construction allows the movable sash when disconnected from the carriage and moved in front of the stationary sash over the flange 62, to be taken out of the window frame any time desired. It will also be noted by referring to Fig. 105-3 how the wood strip 32 is rabbeted at 34a to accommodate the removal of the movable sash at this point. The additional space thus afforded by the rabbeted condition allows the movable sash to give slightly when the weatherstrip 91 is pressed between the two sash frames when the movable sash is in the closed position.

The upturned flange 70 engages a slot in the bottom frame of the movable sash and thus provides a guide for said sash. It also makes the sash waterproof at the bottom.

The top face of the metal trim 71 is provided with a tenon 72. Said tenon holds the upright frame member 27 in position. The tenon is clamped between the upright frame member 27 and the metal strip 39 at the bottom in a manner similar to that in which the tenon 46 is held at the top.

The latter arrangement is very desirable in that it provides for quick detachment of the upright frame member 27 whereby ready access is had for inspection, repair, and adjustment of the screen roller.

The metal trim 71 has a hook shaped edge 73 which hooks over the V-shaped points 74 punched through the window stool moulding 65. This construction holds the metal trim to the window stool at said hooked edge. The other edge of the metal trim is secured to the window stool moulding by screws, the window stool moulding in turn being held to the main frame by the L irons 63 and 64 already described.

On the L iron 64 is secured an iron plate 75 which provides a bearing for the screen roller adjustment device, the latter device being pivoted in the aperture 76. To the plate 75 is fastened a spring 77 which prevents the screen roller from unwinding the spring 11a in the screen roller after it is once adjusted. This construction as stated before is treated in detail in another application.

The window carriage 59 is shown in side and section in Figs. 18 and 19 and its telescopic adaptation to the sash 3 is shown in Fig. 4. Said carriage includes a plate 78, a bar 79 attached

- to the top edge portion of said plate, and a reinforcing bar 80 fastened to the lower portion of said plate, one end of which is provided with a saw-tooth arrangement 83.
- 5 The bar 79 is adapted to be telescoped within the bottom member of the movable sash as shown in Fig. 4 and it is secured thereto by means of screws 81 screwed into holes 81'. The movable sash together with the carriage is supported by the ball bearing rollers 58 which travel in the channel 53 already described, the inside height of the channel being slightly greater than the diameter of the rollers. The spring 66 attached to the hook 67 is to counterbalance the pull exerted by the screen roller spring 11a by virtue of the screen being attached to the movable sash. In the half open position of the movable sash the tension in both springs is about the same.
- 10 20 The ball bearing roller axle 68 is machined eccentrically on the ball bearing adjustment bolt 82, thereby making the carriage structure adjustable.
- 15 Thus by turning the adjustment bolt in a clockwise or counterclockwise direction, the carriage 59 may be raised or lowered as desired.
- 20 The saw tooth arrangement 83 at one end of the bar 80 is to provide in conjunction with the operating handle 84 a locking means for the movable sash, when the latter is in its closed position.
- 25 In Fig. 20 a portion of the carriage is broken away to show the saw tooth portion 83 on the reinforcement bar 80.
- 30 35 Secured to the window stool moulding 65 is a tubular barrel screw holder 85 and screwed into said barrel is a chisel pointed steel screw 86. The point of the screw is adjustable with respect to the height of the saw tooth portion 83 through the aperture 86a.
- 40 The operation of the parts involved in the locking means is as follows:
- 45 When the operating handle 84, as shown in Fig. 4, is pressed downwardly, the eccentric cam 87 is rotated and presses down upon the window stool moulding 65 springing it through the medium of the metal trim 71.
- 50 The latter operation forces the movable sash toward the stationary sash. This movement not only takes out the play which is necessary to allow the movable sash to slide freely, but also prevents rattling and tends to make the structure waterproof as well.
- 55 Furthermore the downward action of the cam on the window stool moulding through the medium of the metal trim acts upon the screw holder to depress it and thereby cause the point of the screw to engage with the saw tooth directly therebelow.
- 60 65 The engagement of the screw with the saw tooth bar locks the carriage as well as the movable sash, thereby making the window jamb-proof.
- 70 75 Window frame construction of this type with a carriage on ball bearing rollers may be used for very large sashes with heavy glass and is practical at times without the use or incorporation of a screen.
- 80 In Fig. 3 a portion of the structure is broken away in order to show the stationary sash in locked position. The locking device whereby the stationary sash is held immovable, comprises a locking lever 88 pivotally mounted to the sash member by means of a screw 89.
- 85 90 There is a plate 90 fastened to the wood strip

33. Said plate contains a locking aperture with which the end of the lever cooperates. Manually inserting the end of the lever in said aperture locks the stationary sash to the strip.

80 A rubber weatherstrip 91 is clamped and screwed to the edge of the stationary sash by a metal strip 92, the rubber strip projecting sufficiently over the side of the sash to make a weather-proof joint between the stationary sash 2 and the movable sash 3 when the latter sash is in its closed position, and is directed toward the glass to prevent the entrance of insects when in a partly opened position.

85 90 The stationary sash is waterproofed and guided at the bottom by means of the pressed angle shape 60 and at the top by the drip lip 30a, the upwardly directed flange of the member 60 engaging the bottom member of the sash in a manner similar to that in which the movable sash is engaged and guided.

95 Thus when the locking lever is released from its locking aperture, the sash may be slid over the guiding flange to the opposite side of the window where the outside of the sash may be washed more readily from the interior of the 100 building.

105 Each of the stationary and movable sashes have a similarly constructed sash frame, Fig. 5 showing a typical sash frame construction for the stationary sash at its side and top and the side members of the movable sash, and Figs. 3 and 4 typical top and bottom sections of the movable sash. The construction of the bottom member of the stationary sash is also shown in Fig. 4. Said frame comprises a deep seated 110 channel member 93 in which the glass 94 is mounted.

115 The glass is held in place by a metal moulding consisting of a looped portion having a straight portion 95 which abuts the glass and a curved portion 96 which abuts the inside flange of the channel to press the straight portion smartly and evenly against the glass.

120 The portion 95 is provided with a flange 97 which on account of its thinness is quite resilient. The portion 96 is folded over as at 98 and is provided with a lip 99 which over-rides the edge of the flange 97.

125 The lip 99 provides a stop against which the flange 97 abuts and also serves to close the gap 125 which would otherwise exist between the straight side and the curved side of the loop.

130 The springing qualities and the compressed condition of the moulding automatically adjusts 130 itself to the accommodation of glass of different thicknesses. This type of moulding is also very easily inserted and detached on account of its peculiar shape. This is one of the striking features which makes this type of window construction practical.

135 In Fig. 3 there is shown a guide plate 106 welded to the web of the channel member 93, said guide travels in the opening formed between the wood strips 32 and 33 to hold the movable sash plumb as it is moved back and forth in the window frame.

140 The channel member 93 for both the movable sash and the stationary sash is slotted to accommodate their travel over their respective guide flanges, the typical condition for each being shown in Fig. 1 and identified by the character 145 101.

145 The glass is inserted in the sash through the opening in which the guide flanges at the bottom extend.

I claim:

1. In a window frame construction, a window stool provided with an upturned flange a portion of which is off-set, a slideable sash, means to engage said sash to said flange whereby it is guided in its sidewise movement, a carriage upon which said sash is mounted, and means to detach said carriage from said sash whereby said sash may be removed bodily from said window frame when said sash is moved over the off-set portion of said flange. 80
- 5 2. In a window frame construction, a sliding sash, a window stool having a flange running end to end of the window opening engaging said sash, a track secured to said stool, and means mounted upon said track for supporting said sash, said means including a carriage, a portion of which is adapted to be telescoped into and fastened to said sash. 85
- 10 3. In a window frame construction, a sash, a carriage upon which said sash is slidably mounted and an operating lever pivotally mounted to said sash and provided with a cam element which when manually rotated will clamp the sash in various adjusted positions to the window frame. 90
- 15 4. In a device of the kind described, a sash having a bottom frame provided with a slot, a follower screen securable to an edge of said sash, there being a housing into which said screen is retractable and from which it is withdrawable, means to shift said sash and said screen in unison, said means including a carriage detachably secured to said sash, spaced ball bearing rollers secured to said carriage and trackage for said rollers whereby said sash is adapted for sidewise movements, a window stool to which the trackage for said rollers is attached, said stool 100 being provided with an upturned flange which engages said slot whereby said sash is guided in its shifting movements, and an operating handle fastened to said sash whereby the shifting of said sash is manually effected. 105
- 20 5. In a device of the kind described, the combination with a slideable sash, of a screen detachably attached to said sash and forming an extension of one edge thereof, said screen being provided at its attaching side with a bar portion of which extends laterally from the screen, there being an aperture in said laterally extending portion, a screw, a portion of the body 110 of said screw being screwed into the edge of said sash, said screw being provided with a locking head which extends through said aperture and a locking lever pivotally mounted to said bar engageable with the body portion of the screw between said head and the laterally extending portion of said bar. 115
- 25 6. In a window frame construction, a sash and a carriage for slidably supporting said sash, a track upon which said carriage is rollingly mounted, a window stool for supporting said track, an operating handle including a cam pivotally mounted to said sash and a locking element actuatable by said cam. 120
- 30 7. In a window frame construction, a sash provided with a slot, a stool having a flange engaging said slot, a carriage, a portion of said carriage being insertable in said sash for attaching said carriage thereto, means for rollingly mounting said carriage to said stool, an operating handle including a cam element mounted to said sash, a window stool moulding including a barrel and a window trim fastened to said moulding, a locking element having a locking point adjustably mounted in said barrel, and a rack carried by said carriage having teeth with which the point of said locking element registers when said cam element is rotated into clamping position with said trim. 125
- 35 8. In a device of the kind described, a sash having a bottom frame provided with a slot, a carriage detachably securable to said sash, rollers eccentrically secured to said carriage and a track for rollingly supporting said rollers to shift said carriage, a window stool to which said track is attached, said stool being provided with an upturned flange which engages said slot, and an operating handle whereby the shifting of said sash is manually effected. 130
- 40 9. In a window frame construction, a sash, a window stool having a flange running end to end of the window opening engaging said sash, a track secured to said stool, and means mounted upon said track for supporting said sash, said means including a carriage, a portion of which is adapted to be fastened to said sash. 135
- 45 10. In a window frame construction, a sliding sash, a window stool having a flange running end to end of the window opening engaging said sash, a track secured to said stool and means mounted upon said track for slidably supporting said sash. 140
- 50 11. In a window frame construction, a sash, a window stool having a flange running end to end of the window opening engaging said sash, a track secured to said stool and a carriage mounted upon said track for slidably supporting said sash. 145
- 55 12. In a window frame construction, a sash, a window stool having a flange running end to end of the window opening engaging said sash, a track secured to said stool and a carriage mounted upon said track for slidably supporting said sash. 150
- 60 13. In a window frame construction, a sash, a window stool, a track secured to said stool a carriage detachably fastened to said sash and slidably mounted upon said track and means including a cam element which when manually rotated will clamp the sash in various adjusted positions to the window frame.

HANS PETER GRONBECH.
